STENCIL PRINTING AND COPYING
MACHINE

Harmon P. Elliott, Watertown, Mass.

Application October 22, 1929. Serial No. 401,487

41 Claims. (Cl. 101—47)

This invention relates to stencils which are used extensively to address envelopes, letters, and the like; and to printing machines involving the use of such stencils.

5 There are at present two different types of stencils or printing devices in extensive use. One type of device is relatively flexible and consists of a paper frame having a window therein occupied by a piece of stencil paper which bears 10 the address or other data to be printed, the paper being imperforate except at the address-impressions and ink being forced through the impressions in the act of printing. The other type of stencil or printing device is relatively rigid and 15 consists of a metal plate having the characters comprising the address embossed therein, the plate being carried by a rigid metal frame and the printing being effected by pressing the embossed plate upon an ink ribbon and thus pressing 20 the ribbon upon the sheet to be printed and effecting the printing thereon.

It is frequently desirable for the user of one type of printing device to adopt the other type 25 of printing device. Since a single user, however, may have thousands of printing devices in his collection, all having different addresses, and since the printing devices oftentimes are also used 30 as index cards as an aid to the user's bookkeeping system, it oftentimes involves a considerable amount of work and expense to make out a collection 35 of one type of printing device prior to discarding the previously used type of printing device. Consequently, an object of the present invention is the provision of an apparatus which is capable of utilizing one type of printing device 40 to transfer its record to the other type of printing device.

The collection of printing devices is usually retained in a predetermined, as alphabetical, or 45 classified, order. Consequently, it is a further object of this invention to provide the apparatus with means by which the printing devices of the type to be discarded form the addresses or equivalent on the different type of printing devices to 50 be adopted and collect the latter devices in the same order in which the devices to be discarded are arranged.

A further object of the invention is the provision 55 of a stencil-copying machine wherein all address-bearing printing devices representing one type are caused to form or copy their addresses on successive printing devices, and particularly stencils which represent a second type.

Another object of the invention is generally to

improve upon stencil forming machines and methods.

Fig. 1 is a front elevation of a machine embodying the present invention.

Fig. 2 is a sectional elevation taken along line 60 2—2 of Fig. 1.

Fig. 3 is a plan view of the machine of Fig. 1.

Fig. 4 is an enlarged sectional detail taken 65 along line 4—4 of Fig. 3, the impression or copying roller of Fig. 3 being advanced from the position shown therein.

Fig. 5 is an enlarged sectional detail taken lengthwise of one of the stencil tracks.

Fig. 6 is a sectional detail across the stencil track guideway of Fig. 5 taken along line 6—6 70 of Fig. 3.

Fig. 7 is a perspective view of the pusher frame for the rigid type of stencil or printing plate.

Figs. 8 through 11 inclusive are views of the 75 impression roller and one of the pushers in the various positions they assume in process of transferring the impression from a printing plate to a stencil.

Fig. 12 is an enlarged fragmentary view similar 80 to Fig. 4 and illustrating the manner in which the printing plate and stencil is brought into address-transferring engagement.

Fig. 13 is a perspective detail of the rocker-frame for reciprocating the impression roller.

Fig. 14 is a plan view of the rigid type of 85 printing plate.

Fig. 15 is a perspective view of the flexible type of stencil.

Fig. 16 is a perspective detail of the pusher 90 for the flexible stencil.

The two types of printing devices with which the present invention is concerned are illustrated in Figs. 14 and 15.

The stencil illustrated in Fig. 15 which is 95 representative of what is herein termed the "flexible" type of stencil consists of a rectangular paper frame 20 having a window 22 therein and a peripheral ledge 24 around the window on which a sheet 26 of stencil paper is secured, the 100 sheet overlying the window. The sheet is composed usually of strong porous paper having a coating of a gelatinous material thereon which is adapted to be cut through by the application of a suitable type character to expose the porous 105 paper under the cut regions thereby to form the stencil characters 28, which may consist of an address. When ink is applied to said stencil sheet by a roller, the ink is forced through the cut portions of the gelatinous coating and 110

through the porous paper therebeneath and onto the sheet or article to be printed, thereby leaving an ink record of the characters borne by the stencil. The printing device illustrated in Fig. 5 14, is representative of what is herein termed the "rigid" type of stencil or printing plate and includes a metal plate 30, which plate is embossed by type characters to present raised printing portions 32, see especially Fig. 12, on one face thereof of which are duplicates of the type characters and in themselves function as type. The plate is adapted to force an inked ribbon against the sheet to be printed and thereby records an impression of the embossed characters 32 on the 10 sheet where the ribbon forcibly engages it. The stencil plate 30 is carried by a rigid metal frame 34. While the address borne by the flexible type of stencil can be read directly from the reverse side of the stencil, this can not be done with 15 the rigid type of printing device; and the characters of the obverse side or working face thereof are reversed so that they can only be read with difficulty. Consequently, the frame 34 usually also carries a paper sheet 36 which bears a duplicate 20 of the address carried by the plate.

The present invention is concerned in its most specific application, with forming on the flexible stencil, by means of the rigid stencil, the address borne by the rigid printing plate.

The machine constructed in accordance with the present invention has holders and guideways for both types of printing devices and means so arranged that pressure is applied to two superimposed rigid and flexible printing devices to cause the address characters of the rigid type of printing plate to cut through the gelatinous coating of the flexible stencil and thereby transfer its impression to the flexible stencil and form the stencil so that the impressed address can be used for printing.

The machine includes the frame 38 which supports the rectangular table 40. A pair of spaced rails 42 having opposed stencil-receiving grooves are located above and are extended lengthwise of the table, and constitute a stencil track along and in the grooves of which successive flexible stencils are caused to be moved from one end to the other thereof. A stencil holder 44 is disposed 45 at the right hand end of the stencil track, see Figs. 1 and 3, and is extended upwardly thereabove and is adapted to support a pile of superimposed flexible stencils. The lowermost stencils are moved in successive order from the pile 50 in the holder and into and along the track and into and out of a printing or copying position therein and into a stencil receiver by a pusher 46 which is shown in perspective in Fig. 16 and which is reciprocated in the direction of the 55 length of the track under the stencil holder and into engagement with the successive lowermost stencils thereof. The particular construction of the pusher is not herein of particular consequence.

The pusher is reciprocated by means of a connecting rod 48 which is pivotally connected thereto and to a crank arm 50 fixed to the upper end of a vertically rotatable shaft 52 that is geared by bevel gears 54 of equal diameter to the shaft 56 of a power mechanism 58 which is well known 60 in the art and need not be further described. Said mechanism is driven by a pulley 57 and the driving connection between it and the output side of the mechanism is under control of a treadle 59, so that proper operation of the treadle stops 70 the rotation of the shaft 56 and also the opera-

tion of the impression means presently to be described. As thus arranged, each complete rotation of the shaft 56 causes a complete reciprocatory movement of the stencil pusher.

After the flexible stencils have been moved along the track into and out of a printing or copying position intermediate the ends of said track they are moved into a stencil elevating mechanism 60 which serves to raise the stencils and to deliver them into a stencil receiver 62. Said stencil raising mechanism includes a pair of side plates 64 which are spaced apart lengthwise of the stencil track and have arcuate grooves 66, see especially Fig. 2, therein into which the opposite ends of the stencils are adapted to be located. A rotatable shaft 68 carries a pair of arms 70 which engage a side edge of the stencil and move it upwardly along said arcuate groove 66 and into the spiral grooves 72 of elevating worms 76 that are disposed in communication with the upper ends of said grooves 66. Said worms serve to raise the stencil upwardly and to position it at the bottom of the pile of stencils in the holder 62. The worms also constitute the supporting means for the pile of stencils therein. The worms are geared to the shaft 68 by bevel gears 78. Said shaft is driven by a chain 80 from a drive shaft 82 and at the same speed therewith. Said shaft 82 is driven by a chain 84 from and at the speed of the shaft 56 of the power mechanism so that both the elevating mechanism and the stencil pusher positively operate in timed relation with each other. The elevating mechanism and the elevated stencil holder 62 are in themselves old in the art and can be constructed, for example, 100 as shown in the Sterling Elliott Patent No. 1,210,440, dated January 2, 1917.

The mechanism thus described operates to move successive flexible stencils from one holder to the other and into and out of copying position 115 and to hold them momentarily stationary in copying position during the return stroke of the stencil pusher.

The rigid printing plates are guided for movement under the flexible stencils in a line at right angles thereto. The rigid plates are moved along a guide frame 86, see Figs. 2, 3 and 6, which is secured by ears 88 to the underside of the table 40 under a transversely-elongated opening 120 therein. The frame 86 consists of a pair of guide members 90 connected by one or more integral cross bars 92 having opposed seats 94 on which the frames 34 of the plates are supported and moved. A holder 96 for the plates is disposed 125 above the rear end of the guide frame and is adapted to hold a pile of superimposed plates.

The feeding means for the printing plates includes a reciprocating frame having a pair of spaced connected side bars 98 which are slidably received in grooves 100 of the guide frame 90. Said bars are provided with a plurality of forwardly extended spring-urged dogs 102 which are adapted to engage the rear edges of the plates in the guide frame as shown in Figs. 2 and 5 and move the plates forwardly as the frame is 140 moved forwardly and to pass under the plates as the frame is moved rearwardly. The guide frame for the plates extends immediately under the stencil track for the flexible stencils as is illustrated particularly in Figs. 4 and 12, and the 145 printing plates are adapted to be stationary therein while the feeding frame is being reciprocated rearwardly, thereby to permit the printing or copying operation of the printing plate on a flexible stencil. The plates are moved forwardly 150

beyond the aforesaid printing position and are deposited on a movable conveyor belt 104 where they are conveyed away from the machine and can be collected in a receptacle 105, to be subsequently retained or discarded.

The guide frame 86 is provided with a solid transverse member 106, see Figs. 2, 4, and 12, which underlies the printing plates when they are in printing position beneath the track for the flexible stencils and constitutes a platen or anvil which supports them rigidly against the pressure of the printing or embossing mechanism hereinafter to be described. The construction of the holders and guiding and feeding mechanism for the printing plates is or can be common in the art.

The feeding frame for the printing plates is operated by mechanism which includes a link 108 pivotally connected to a rod 110 extended between ears 112 that depend below the side bars 98. Said link is extended rearwardly and is pivotally connected with the upper end of a generally vertical lever 114 which is pivoted at its lower end on a pin 116 carried by a depending bracket or stirrup 118 of the guide frame 86. Said lever is reciprocated forwardly and rearwardly by a connecting rod 120 which is pivoted to said lever intermediate its ends and is extended forwardly and is pivotally connected to the upper end of a lever 122, which lever is fixed to a shaft 124 journaled in a depending bracket 126 secured to the underside of the table 40. The lower end of said lever 122 is pivotally connected to a rod 128 which extends downwardly and forwardly to and is reciprocated by the power mechanism 58 in a well known manner and is so timed with respect to the operation of the shaft 56 of the power mechanism that both the rigid and flexible printing devices are moved forwardly from their respective holders in unison.

The belt 104 is advanced in a step-by-step manner in one direction by a pawl arm 105 which is pivoted on the belt-supporting shaft 107 and has a spring-urged pawl 109 which engages a ratchet 111 fixed to said shaft. Said arm has a pin and slot connection 113 with an arm 115 fixed to the reciprocatory shaft 124 such that each reciprocatory movement thereof in one direction advances the belt by a distance that is somewhat greater than the length of a flexible stencil.

Mechanism is provided to urge two superposed printing devices into forcible engagement when they are in copying position whereby to cause the embossed characters carried by the printing plate to cut through the gelatinous coating of the stencil and thereby form the printing characters of the plate in the stencil, whereby to condition it for printing such characters. The mechanism to accomplish this result includes a roll 130 which is disposed between the rails 42 of the track for the stencils and is movable lengthwise of said track in pressure-applying engagement with the stencils therein. The length of the roller is somewhat less than the width of the window 22 in the stencil so that the roller engages only the stencil sheet 26 of the stencil. The roller is made of hard metal, as steel, and the surface thereof preferably is knurled to provide a series of points of projections being so closely spaced, or the knurling being so fine, that it cannot be clearly illustrated herein.

The roll is mounted between and is rotatably supported in the forks 132 of a frame 134 which is connected by a rod 136, which is adjustable as to

length, to a cross bar 138 which is located between and pivoted to the upper ends of spaced arms 140 that constitute an operating frame for reciprocating the roller. Said arms are pivoted intermediate their ends to a bracket 142 depending from the table. Said frame is connected by a connecting rod 144 that is pivotally connected to the lower ends of said arms to a crank pin 146 carried by a horizontally rotatable gear 148 journaled in the bracket 150. Said gear is driven at half speed by a pinion gear 152 fixed to the shaft 52. The radial line between the crank pin 146 and the axis of the gear 148 is displaced approximately 45° with respect to the crank arm 150 that operates the stencil pusher, in the setting of the parts illustrated in Fig. 1. With this arrangement, the roller 130 is caused to roll over the stencils only while the pusher is moving backward, or to the right, Fig. 1, and remains beyond the position occupied by the stencils, at one end or the other thereof, when the pusher is moving forward to deliver a new stencil into printing position. The periods of rest or inactivity of the roller are obtained when the gear 148 is moving the crank pin 146 across dead center, on both sides of the gear. While the roller is not actually motionless, at such times, its extent of movement is so small that it does not come into engagement with a moving stencil. The extent of "dead-center" movement of the gear 148 is approximately 90°.

Mechanism is provided to hold the roll in pressure applying relation with the two printing devices and also to cause the roll to move upwardly above the devices as it moves beyond both ends thereof so that the devices can then move freely in their tracks. Said mechanism includes a pair of upstanding horizontal plates 160 which are extended lengthwise of the stencil track 42 on opposite sides thereof and are fixed to the table 40 by the bolts 162. Cam bars 164 are carried by said plates, on the confronting faces thereof, and have cam grooves therein which have horizontal sections 172 and elevated dwell sections 174 at the opposite ends of the horizontal sections. The horizontal sections are at least as long as the length of the address space of the stencils. The ends of the roller shaft 131 are located in said grooves and have flanged cam rolls 176 thereon which ride in engagement with the cam faces of said bars. When the roll is located at one side or the other of the printing position, the cam rollers 176 are in the elevated dwell portions 174 of the bars and the roll is elevated into a position above and out of contact with the flexible stencils, and beyond the ends of the stencils, or at least beyond the address-portions thereof. When the roll is moved across the printing position, the cam rolls 176 engage and ride over the cam faces 172 of said bars and consequently the roll 130 is depressed to force the flexible stencil into pressure-applying engagement with the printing plate, as illustrated in Fig. 12, the stencil sheet of the flexible stencil being flexed between its frame to permit such engagement. The pressure exerted by the roll 130 between the two printing devices is adapted to be sufficient to cause the embossed characters of the printing plate to cut through the gelatinous coating of the stencil and thereby transfer its address to the stencil. The knurling of the roll 130 facilitates this operation as it increases the unit pressure between the stencils at the points of contact. The knurling is also important in that it prevents the complete severing of the material within the outline of the letter from the body of the stencil sheet, which mate-

rial, in letters like "O", "D", for instance, might otherwise drop out of the body of the stencil sheet. By causing the roll to move lengthwise of the stencil, the stencil is caused to engage but 5 few areas of the type characters of the printing plate at a time so that strong unit pressure can be obtained to effect the transferring operation. It will be appreciated that the two types of printing devices are moved in their guideways in such 10 manner that the length of the stencil extends lengthwise of the address carried by the printing plate.

The various steps in the transferring operation are illustrated in Figs. 8 through 11 inclusive. 15 Fig. 8 illustrates the position of a flexible stencil, the impression roller and the pusher for the flexible stencil at the time the pusher is at the extreme end of its operating stroke and has moved a stencil into printing position to the left 20 of the impression roll 130. The pusher then moves backwardly or to the right and the roll moves to the left over and in pressure applying engagement with the stencil and into a position beyond and above the stencil and at the left 25 thereof. The pusher then makes a second operative stroke and pushes a second stencil into position, the feeding mechanism for the rigid printing plates being also at the same time moving a plate into position under a stencil. During this 30 movement, the impression roll remains stationary. The pusher then returns to the right and the impression roll also moves to the right and rolls over the into engagement with the stencil, thus cutting into the stencil, the addressed data carried 35 by the printing plate. The impression roll moves in opposite directions in engagement with alternate flexible stencils.

With this machine, the stencils are cut and 40 deposited in the stencil holder in the same order that the printing plates are presented to the printing position so that the addresses borne by the printing plate collection are transferred to the collection of stencils without disarranging the 45 order in which the addresses appear in the collection.

I claim:

1. In a stencil copying machine, supporting 50 means for a blank printing device, supporting means for a formed address-bearing printing device, means which includes a formed printing device to form on the blank printing device the same address that is carried by said formed printing device, and means for moving successive blank and address-bearing printing devices separately into and out of forming position.

2. In a stencil copying machine, supporting 60 means for a blank printing device, supporting means for a formed address-bearing printing device, and means to form the blank printing device for printing purposes, including means to position successive blank and address-bearing devices separately in confronting relation with each other, and means to urge the two devices in address-forming engagement.

3. In a stencil copying machine, supporting 65 means for a blank stencil, supporting means for a formed address-bearing plate, means including a formed plate to impress its address on and form the blank stencil with the same address thereon, and means for moving successive stencils and plates separately into and out of forming position.

4. In a stencil copying machine, supporting 70 means for a blank stencil, supporting means for a formed address-bearing plate, means including

said formed plate to cut the address characters thereof into and thereby form the blank stencil, and means for moving successive stencils and plates separately into and out of address-forming position.

5. In a stencil copying machine, supporting 80 means for a blank stencil having a stencil sheet, supporting means for a formed address-bearing plate having embossed address characters, means to press the address characters of the formed plate on the stencil sheet of said blank stencil and thereby form it for printing uses, and means to move successive stencils and plates separately into and out of address-forming position.

6. In a stencil copying machine, means to hold 85 in registration a blank stencil having a stencil sheet, and a formed address-bearing plate having embossed address characters, means to form the blank stencil with the address of the formed plate including means to press the embossed address characters of the formed plate into forcible and address-forming engagement with the stencil sheet of the blank stencil, and means to move successive stencils and plates separately into and out of address-forming position.

7. In a stencil copying machine, means to hold 90 in registration a blank printing device and a formed address-bearing printing device, means to form the blank device with the address of the formed device including means to press the address-bearing portion of the formed device into forcible and address-forming engagement with the printing portion of the blank device, and means to move successive blank and address-bearing printing devices separately into address-forming position.

8. In a stencil copying machine, means to move a succession of blank stencils into and out of address-copying position, means to move a succession of address-bearing printing devices 115 into and out of address-copying position, and means operating when they are in such position to form the addresses borne by successive printing devices on successive blank stencils whereby to condition said latter stencils for printing such addresses.

9. In a stencil copying machine, means to move a succession of blank stencils into and out of address-copying position, means to move a succession of address-bearing printing devices 125 into and out of address-copying position, and means operating when said stencils and printing devices are in such positions to impress the addresses of successive printing devices on successive blank stencils whereby to condition said 130 stencils for printing such addresses.

10. In a machine for forming address-bearing stencils, means to move successive blank stencils into and out of an address-forming position, means to move a succession of address-bearing devices 135 into and out of register with the stencils in said forming position, and means located at the forming position to form the addresses borne by successive address-bearing devices on successive blank stencils.

11. In a stencil forming machine, means to move successive blank stencils into and out of an address-forming position, means to move a plurality of address-bearing devices into cooperative relation with said blank stencils, and means to form the addresses borne by successive devices on successive blank stencils whereby to condition said stencils for printing such addresses.

12. In a stencil copying machine, means to 145

- move successive flexible stencils having blank stencil sheets into and out of an address forming position, means to move successive rigid address plates formed with embossed address-characters 80
- 5 into and out of cooperative relation with said stencils, and means to form the addresses borne by successive rigid plates on the blank stencil sheets of successive flexible stencils and to condition such flexible stencils for printing said 85
- 10 addresses.
13. A stencil copying machine including means to move successive stencils having blank stencil sheets into and out of an address forming position, means to move successive printing plates having embossed address characters thereon into and out of cooperative relation with said stencils, and means including said plates to form the addresses thereof on said stencils including means to press the address characters of successive plates upon the blank stencil sheets of successive stencils and to form said sheets for printing with such address characters. 90
14. In a stencil copying machine, means to move into and out of forming position successive stencils having frames and blank stencil sheets carried thereby provided with gelatinous coatings, means to move a collection of rigid plates formed with embossed address characters into and out of cooperative relation with said stencils, and means to form successive blank stencils with the addresses of successive formed plates including means to force the embossed address characters of successive plates through the gelatinous coatings of the stencil sheets of successive blank stencils. 100
15. In a stencil copying machine, supporting means for a blank printing device, means to support a formed address-bearing printing device in registration with and spaced from said blank device, means to form the blank device for printing with the address of said formed device including means to press the printing portions of both stencils progressively into pressure-applying and address-transferring engagement, and means to move successive blank and address-bearing printing devices separately into address-forming position. 105
16. In a stencil copying machine, supporting means for a blank stencil, means to support a formed address-bearing plate having a line of embossed address characters in opposed relation to the blank stencil, means to form said blank stencil for printing with the address borne by said formed plate including means to press the address characters of the formed plate in a progressive manner lengthwise of the line of characters and in address forming relation with the blank stencil, and means separately to move the stencils and the plates into registration at the address-forming position at times when there is no pressure on the stencils and plates. 115
17. In a stencil copying machine, supporting means for a blank printing device, means to support a formed address-bearing printing device having a line of embossed address characters in opposed relation to the blank device, and means to form said blank device for printing with the address borne by said formed device including means to press the address characters of the formed device in a progressive manner and in address forming relation with the blank device, including a pressure-applying roll, means to move the roll from one end to the other of and in engagement with the blank stencil and lengthwise of the line of address characters, and means 120
- to move the blank and address-bearing devices separately into address-forming position at times when said roll is free from engagement with said devices. 125
18. In an addressing machine, means to feed successive printing devices into and out of active position, which printing devices have lines of address characters extended lengthwise of the devices, means to feed successive stencils into and out of active position, and means to operate on successive printing devices and stencils including a roll which is movable lengthwise of the address portion of successive stencils and the lines of address characters of the devices and in pressure applying relation with said stencils and devices. 130
19. In an addressing machine, means to move successive address-bearing printing devices into and out of active position, means to move successive blank devices to be addressed into and out of cooperative relation with said printing devices, and means to impress the addresses of successive printing devices on successive blank devices including a roll which presses successive blank devices and printing devices into engagement with each other, and means to move said roll lengthwise of the address portions of said printing devices while in such pressure-applying relation therewith. 135
20. In an address copying machine, means to move successive address-bearing printing devices into and out of an address-copying position, means to move successive blank stencils into and out of such position in cooperative relation with said address-bearing printing devices, and means to press successive blank and address-bearing printing devices into forcible engagement and to form the blank stencils for printing with the addresses borne by the address-bearing printing devices including a roller having means to urge successive stencils and printing devices into engagement, and means to move said roller over said stencils and printing devices while holding them in pressure engagement. 140
21. In an address copying machine, a holder adapted to contain a collection of formed address-bearing printing devices, means to move successive printing devices from said holder into and out of a copying position, a second holder adapted to contain a collection of blank printing devices, means to move successive blank printing devices from said holder into and out of the copying position and in operative position with said formed printing devices, and means including successive formed printing devices to form the addresses in successive blank printing devices and prepare them for printing such addresses. 145
22. In an address copying machine, a holder adapted to contain a collection of formed address bearing printing devices, means to move successive printing devices from said holder into and out of a copying position, a second holder adapted to contain a collection of blank printing devices, means to move successive blank printing devices from said holder into and out of the copying position and in operative position with said formed printing devices, and means including successive formed printing devices to form the addresses in successive blank printing devices and prepare them for printing such addresses, said means including means to urge successive blank printing devices into pressure-applying and address-forming engagement with said formed printing devices. 150

23. In an address copying machine, a holder adapted to contain a collection of formed address-bearing printing devices, means to move successive printing devices from said holder into and out of a copying position, a second holder adapted to contain a collection of blank printing devices, means to move successive blank printing devices from said holder into and out of the copying position and in operative position with said formed printing devices, and means including successive formed printing devices to form the addresses in successive blank printing devices and prepare them for printing such addresses including an address-forming roll, means to urge said roll forcibly against successive blank printing devices whereby to force them upon successive formed printing devices, and means to move said roll across said printing devices while in such relation therewith. 80
24. In a stencil copying machine, a holder for a collection of printing devices consisting of plates having embossed address characters therein, means to move successive printing devices into and out of a stencil copying position, a holder for a collection of blank stencils having blank stencil sheets, means to move successive blank stencils into and out of cooperative relation with said printing devices, and means to press the blank stencil sheets of successive printing devices against the embossed address characters of successive printing devices and in address-forming relation with such devices. 85
25. In a stencil copying machine, a holder for a collection of printing devices consisting of plates having embossed address-characters therein, means to move successive printing devices into and out of a stencil copying position, a holder for a collection of blank stencils having blank stencil sheets, means to move successive blank stencils into and out of cooperative relation with said printing devices, means to press the blank stencil sheets of successive printing devices against the embossed address characters of successive printing devices and in address-forming relation with such devices. 90
26. In a stencil copying machine, means to feed successive formed address-bearing printing devices into and out of a copying position, means to feed successive blank address-receiving printing devices into and out of said copying position and into and out of cooperative relation with successive forming devices, and means to urge said successive formed and blank devices into copying engagement including a roller, means to urge the roller into pressure applying engagement with said devices, means to move the roller from one end to the other of said devices, and automatically-operative means to move the roller from such pressure-applying engagement when it is in opposite ends of said devices. 95
27. In a stencil copying machine, means to feed successive formed address-bearing printing devices into and out of a copying position, means to feed successive blank address-receiving printing devices into and out of said copying position and into and out of cooperative relation with successive formed printing devices, and means to urge said successive formed and blank devices into copying engagement including a roller, means to urge the roller into pressure-applying engagement with said devices, means to move the roller from one end to the other of said devices, and automatically-operative means to move the roller from such pressure-applying engagement when it is in opposite ends of said devices. 100
28. In a stencil copying machine, means to feed successive formed address-bearing printing devices into and out of a copying position, means to feed successive blank address-receiving printing devices into and out of said copying position and into and out of cooperative relation with successive formed devices, and means to urge said successive formed and blank devices into printing engagement including a roller, means to move the roller lengthwise of said devices into pressure-applying engagement therewith, and cam means cooperating with said roller to hold it in pressure-applying engagement during part of the movement of said roller and to affect its movement out of such pressure-applying relation at each end of its extent of movement. 105
29. In an addressing machine, means to transfer the address of a formed printing device to a blank printing device including a roller, means to move said roller from one end to the other of said formed device upon and in rolling engagement with said blank device, means to hold said blank and formed devices from movement in the direction of movement of said roller, and means subsequently to move the two devices out of the operating range of said roller. 110
30. In an addressing machine, means to transfer the address of a formed printing device to a blank printing device including a roller, means to move said roller from one end to the other of said formed device upon and in rolling engagement with said blank device, and means to hold said devices from movement in the direction of movement of said roller, said means including a guideway along which said formed device is movable and which guideway is extended transversely of the line of movement of said roller. 115
31. In an addressing machine, means to transfer the address carried by a formed printing device onto a superposed blank address-receiving printing device including a roller located above said blank device, means to move said roller lengthwise of and also vertically into and out of engagement with said blank device including means for moving the roller lengthwise of said blank device, and cam means over which the roller is movable including a pair of cam bars disposed on opposite sides of the roller and extended in the direction of movement thereof, said cam bars having depressed working faces which are engaged by said roller during its movement across said blank device to hold the roll in pressure applying engagement therewith, said bars also having elevated dwell portions at the ends of said working faces which raise said roller out of pressure-applying relation with said blank device. 120
32. In a stencil forming machine, a guideway, means to move successive formed address-bearing printing devices along said guideway, a stencil track located above said guideway, means to move successive blank stencils along said track and into and out of cooperative relation with successive address-bearing printing devices in said guideway, and means to urge successive blank stencils into engagement with successive address-bearing printing devices and into address-forming relation therewith including a roller which is located above and is movable lengthwise of said blank stencils in rolling engagement therewith, means 125
33. In a stencil forming machine, a guideway, means to move successive formed address-bearing printing devices along said guideway, a stencil track located above said guideway, means to move successive blank stencils along said track and into and out of cooperative relation with successive address-bearing printing devices in said guideway, and means to urge successive blank stencils into engagement with successive address-bearing printing devices and into address-forming relation therewith including a roller which is located above and is movable lengthwise of said blank stencils in rolling engagement therewith, means 130
34. In a stencil forming machine, a guideway, means to move successive formed address-bearing printing devices along said guideway, a stencil track located above said guideway, means to move successive blank stencils along said track and into and out of cooperative relation with successive address-bearing printing devices in said guideway, and means to urge successive blank stencils into engagement with successive address-bearing printing devices and into address-forming relation therewith including a roller which is located above and is movable lengthwise of said blank stencils in rolling engagement therewith, means 135
35. In a stencil forming machine, a guideway, means to move successive formed address-bearing printing devices along said guideway, a stencil track located above said guideway, means to move successive blank stencils along said track and into and out of cooperative relation with successive address-bearing printing devices in said guideway, and means to urge successive blank stencils into engagement with successive address-bearing printing devices and into address-forming relation therewith including a roller which is located above and is movable lengthwise of said blank stencils in rolling engagement therewith, means 140
36. In a stencil forming machine, a guideway, means to move successive formed address-bearing printing devices along said guideway, a stencil track located above said guideway, means to move successive blank stencils along said track and into and out of cooperative relation with successive address-bearing printing devices in said guideway, and means to urge successive blank stencils into engagement with successive address-bearing printing devices and into address-forming relation therewith including a roller which is located above and is movable lengthwise of said blank stencils in rolling engagement therewith, means 145
37. In a stencil forming machine, a guideway, means to move successive formed address-bearing printing devices along said guideway, a stencil track located above said guideway, means to move successive blank stencils along said track and into and out of cooperative relation with successive address-bearing printing devices in said guideway, and means to urge successive blank stencils into engagement with successive address-bearing printing devices and into address-forming relation therewith including a roller which is located above and is movable lengthwise of said blank stencils in rolling engagement therewith, means 150

- to reciprocate said roller from one end to the other of said blank stencils, and means to hold said roller in pressure-applying engagement with said blank stencils.
- 5 33. In a stencil forming machine, a guideway, means to move successive formed address-bearing printing devices along said guideway, a stencil track located above said guideway, means to move successive blank stencils along said track and into and out of cooperative relation with successive address-bearing printing devices in said guideway, and means to urge successive blank stencils into engagement with successive address-bearing printing devices and into address-forming relation therewith including a roller which is located above and is movable lengthwise of said blank stencils in rolling engagement therewith, means to reciprocate said roller from one end to the other of said blank stencils, and means to hold said roller in pressure-applying engagement with said blank stencils including a pair of horizontal cam bars which are located on opposite sides of and above said roll and are extended lengthwise of said track, said bars having raised dwell portions at each end thereof and depressed intermediate working portions, and means to move said roller lengthwise of said cam bars from one end to the other thereof, and into and out of said dwell and working portions, whereby to move said roller into and out of pressure-applying engagement with said stencils. 80
- 10 34. In an addressing machine, means to move successive address-bearing printing devices into and out of an addressing position, means to address from successive devices when they are in addressing position including a roller, means to move the roller in opposite directions across successive devices from one end to the other thereof, means to hold the roller stationary periodically at opposite ends of its path of travel, and means to operate said device moving means to move successive devices into addressing position during such stationary periods of said roller so that said roller operates on successive devices at each of its movements in opposite directions. 85
- 15 35. In a stencil forming machine, means to move successive formed address-bearing printing devices into and out of a forming position, means to move successive blank stencils into and out of forming position and into and out of cooperative relation with said formed devices, and means to form successive blank stencils for printing with the successive formed devices including a roller, and means to move the roller alternately in opposite directions across and in pressure applying relation with successive formed devices and blank stencils. 90
- 20 36. In a stencil forming machine, means to move successive formed address-bearing printing devices into and out of a forming position, means to move successive blank printing devices into and out of forming position and into and out of cooperative relation with said formed printing devices, and means to form successive blank printing devices for printing with the addresses of successive formed printing devices including a roller, means to move the roller alternately in opposite directions across and in pressure-applying relation with successive formed and blank printing devices, and from one end to the other of said blank printing devices. 95
- 25 37. In a stencil forming machine, means to move successive formed address-bearing printing devices into and out of a forming position, means to move successive blank printing devices into and out of forming position and into and out of cooperative relation with successive formed printing devices including a roller, means to move the roller alternately in opposite directions across and in pressure-applying relation with successive formed and blank printing devices, and from one end to the other of said blank printing devices. 100
- 30 38. In an addressing machine, separate means for moving different sets of printing devices successively into an addressing position, a roller operable on the devices at the addressing position, and means to move the roller in opposite directions lengthwise of the devices and into and out of engagement therewith including means to hold the roller periodically stationary at each end of the addressing position during movements of the devices. 105
- 35 39. In an addressing machine, separate means for moving different sets of printing devices successively into an addressing position, a roller operable on the successive devices at the addressing position, means to move the roller in opposite directions lengthwise of the devices from one end to the other of the addressing position and into and out of engagement with the devices, and means permitting movement of said roller on both sides of but not in the addressing position during movements of the devices. 110
- 40 40. In an addressing machine, separate means for moving sets of different printing devices successively into and out of an addressing position, a roller operable on the devices at the addressing position, means to move the roller in opposite directions lengthwise of the devices from one end to the other of the addressing position and into and out of engagement with the devices when they are stationary including a crank for reciprocating said roller, a driving shaft, and means for rotating said crank positively at half the speed of said driving shaft, said device moving means for one set of devices including a pusher and means including a crank driven by said driving shaft and at the speed thereof for reciprocating the pusher. 115
- 45 41. In an addressing machine, means for moving sets of different printing devices successively into and out of an addressing position, a roller operable on the devices at the addressing position, means to move the roller in opposite directions lengthwise of the devices from one end to the other of the addressing position and into and out of engagement with the devices when they are stationary including a crank for reciprocating said roller, a driving shaft, and means for rotating said crank positively at half the speed of said driving shaft, said device moving means for one set of devices including a pusher and means including a crank driven by said driving shaft at the speed thereof for reciprocating the pusher, said cranks being angularly displaced whereby the movement of said roller is relatively small when it is at the ends of the addressing position and the devices are moving and is relatively large when the roller is traversing the addressing position and is in engagement with the stationary devices. 120
- 50 42. In a stencil forming machine, means to move successive formed address-bearing printing devices into and out of a forming position, means to move successive blank printing devices into and out of forming position and into and out of cooperative relation with successive formed printing devices including a roller, means to move the roller alternately in opposite directions across and in pressure-applying relation with successive formed and blank printing devices, and from one end to the other of said blank printing devices. 125
- 55 43. In a stencil forming machine, means to move successive formed address-bearing printing devices into and out of a forming position, means to move successive blank printing devices into and out of forming position and into and out of cooperative relation with successive formed printing devices including a roller, means to move the roller alternately in opposite directions across and in pressure-applying relation with successive formed and blank printing devices, and from one end to the other of said blank printing devices. 130
- 60 44. In a stencil forming machine, means to move successive formed address-bearing printing devices into and out of a forming position, means to move successive blank printing devices into and out of forming position and into and out of cooperative relation with successive formed printing devices including a roller, means to move the roller alternately in opposite directions across and in pressure-applying relation with successive formed and blank printing devices, and from one end to the other of said blank printing devices. 135
- 65 45. In a stencil forming machine, means to move successive formed address-bearing printing devices into and out of a forming position, means to move successive blank printing devices into and out of forming position and into and out of cooperative relation with successive formed printing devices including a roller, means to move the roller alternately in opposite directions across and in pressure-applying relation with successive formed and blank printing devices, and from one end to the other of said blank printing devices. 140
- 70 46. In a stencil forming machine, means to move successive formed address-bearing printing devices into and out of a forming position, means to move successive blank printing devices into and out of forming position and into and out of cooperative relation with successive formed printing devices including a roller, means to move the roller alternately in opposite directions across and in pressure-applying relation with successive formed and blank printing devices, and from one end to the other of said blank printing devices. 145
- 75 47. In a stencil forming machine, means to move successive formed address-bearing printing devices into and out of a forming position, means to move successive blank printing devices into and out of forming position and into and out of cooperative relation with successive formed printing devices including a roller, means to move the roller alternately in opposite directions across and in pressure-applying relation with successive formed and blank printing devices, and from one end to the other of said blank printing devices. 150
